UNITED STATES PATENT OFFICE.

JOHN W. MEAKER, OF CHICAGO, ILLINOIS, ASSIGNOR TO C. CLARENCE POOLE, TRUSTEE, OF EVANSTON, ILLINOIS.

COIN HOLDING AND DELIVERING MACHINE.

No. 799,351.

Specification of Letters Patent.

Patented Sept. 12, 1905.

Application filed October 17, 1904. Serial No. 228,848.

To all whom it may concern:

Be it known that I, JOHN W. MEAKER, a citizen of the United States, residing at Chicago, in the county of Cook and State of Illinois, have invented certain new and useful Improvements in Coin Holding and Delivering Machines; and I do hereby declare that the following is a full, clear, and exact description thereof, reference being had to the accompanying drawings, and to the letters of reference marked thereon, which form a part of this specification.

My invention relates to composite coin holding, counting, and change-making machines wherein coins of various sizes and denominations are stacked in a plurality of grooves or trough-like receptacles provided with individual coin-ejecting mechanisms.

The machine illustrated in the accompanying drawings embodies a desirable form of apparatus, in which is contained the several features included in my invention. In said machine the coin-holding receptacles are inclined upwardly and rearwardly from their forward or delivery ends. Means are also included whereby the coins in each trough are advanced toward the forward or delivery ends of the troughs and the ejecting mechanisms there located, which means consist of gravity-acting slides adapted to press at their forward ends against the rear ends of the stacks of coins in the troughs in such manner as to maintain at all times the advance or lowermost coin of each stack in a position to be acted upon by its ejecting mechanism. The said gravity-acting slides are provided with coin-receptacles, so that said slides serve also as coin counting and storing devices.

My invention consists in the matters particularly pointed out in the appended claims.

Figure 1 is a view in perspective showing a portion of a machine embodying the main features of my invention. Fig. 2 is a perspective view of one of the improved gravity-acting slides, showing the same detached from the machine. Fig. 3 is a longitudinal vertical section of the machine, taken on line 3-3 of Fig. 1. Fig. 4 is a fragmentary view in elevation of the ejecting or lower front end of the coin-grooves, showing the gravity-slides and coins removed. Fig. 5 is a fragmentary sectional view taken on line 5-5 of Fig. 3.

The apparatus embodying my invention shown in the accompanying drawings includes

a supporting stand or base consisting of lateral frame-plates A A, extending from front to rear of the machine and connected at their forward ends by a horizontal front plate A'. The rear portion of the machine is desirably unprovided with an inclosing or end wall and the frame-plates A A are connected only at their front and top edges. The upper top margins of the frame-plates A A are continuously inclined upwardly from front to back and carry on their upper inclined edges a top plate B, which spans the inclosure formed by the said frame-plates A A and the front plate A'. The said top plate B is provided with laterally-projecting flanges b, which overhang the upper inclined margins of the frame-plates A and are secured thereto by countersunk screws or other suitable securing means. Said flanges b preferably extend throughout the length of the plate B at either side margin thereof and are provided at their forward ends with elevated projections b', desirably equal in width to said flanges and which in the device shown are formed integral therewith. The said top plate B is provided with parallel longitudinally-disposed troughs or grooves b², extending throughout its length, which serve as coin-receptacles and in which the coin used in making change is stacked. The walls of said troughs b² are preferably V-shaped in cross-section and are provided at their upper margins with longitudinal inwardly-projecting flanges b³, adapted for engagement with gravity-acting slides, as will hereinafter more fully appear. The troughs b² are divided by upwardly-extending flanges b⁴, provided at their lower or front ends with elevated projections b⁵, similar to those formed upon the flanges b. The troughs so formed in the top plate B are uniform in size throughout their length and the several troughs are adapted to receive coins of different denominations, the widest groove in the machine shown being adapted to receive half-dollars, the next smaller to receive quarters, and the remaining troughs being each of gradually lessening size for coins of smaller denominations.

Now referring to the construction of the parts at the forward or delivery ends of the troughs b² b², said troughs are provided with end walls a a, against which rest the forward ends of the stacks of coins in the troughs, said end walls being provided with slots ar-

ranged centrally with respect to the troughs through which the movable parts of the ejecting devices pass in acting on the coins. In the particular construction shown the said 5 end walls a consist of integral extensions of the front frame-plate A', which extensions are bent downwardly and outwardly along the line of the upper margin of said plate to form the forwardly-directed part a^4 and are then bent upwardly to form the end walls a . The upper ends of said extensions are preferably narrowed to form prongs a^4 , which are bent over the top surfaces of the upwardly-projecting parts b' and b^5 .

15 The ejecting mechanism whereby coins from each stack may be delivered one by one into the hand of the operator during the operation of making change, as shown in the accompanying drawings, are made as follows:

20 C is a horizontal shaft which is journaled at its ends in apertures formed in the side frame-plates A A and which engages between its ends lugs b^6 b^6 , which depend from the top plate B. As before stated, each trough is 25 provided with independently-operating mechanism for ejecting coins, and two lugs are preferably provided below each trough, said lugs being spaced at equal distances from the centers of the troughs. Between the lugs b^6 30 and below each trough is mounted a lever C', which extends outwardly through guide-slots a^2 , formed in the front frame-plate A'. The lever C' at its inner end is pivotally mounted on the shaft C, and it is provided at its outer 35 end with an integral extension c , bent at right angles to the body portion of the levers, and also with an outwardly or forwardly extending finger-piece or key c' , adapted to be engaged by the finger of the operator in the 40 act of ejecting the coin. The unit of value of the coin contained in the groove with which each finger-piece is associated may be stamped or otherwise applied to said finger-piece. The levers C' are formed of a single strip of 45 sheet metal having lateral upwardly-bent side flanges C², apertured for the passage of the shaft C, said flanges serving to stiffen the lever. Upon the upwardly-bent portion c of the lever C is pivotally mounted a coin-ejecting 50 lever D, having a coin-ejecting finger d , adapted to project within the slot formed in the end wall a a sufficient distance to engage the periphery of the lowermost or advance coin in the trough. The said levers D are 55 provided with shoulders d' , which engage the outer faces of the walls a to prevent the finger d from projecting into troughs a distance sufficient to engage more than one coin at a time. The ejector-lever D is pivoted upon 60 inwardly-projecting lugs c^3 and extends below its pivotal connection to a point adjacent to the main body of the lever C', where it is bent upon itself in a U-shaped formation to constitute a counterweight. By reference to 65 Fig. 3 it will be seen that the ejecting-lever

D normally assumes an inclined position and that its weighted lower end d^2 serves at all times to yieldingly hold the shoulders d' in contact with the outer surfaces of the end walls a and to insure engagement of the ejecting-finger with the forward or advance coin in the trough. 70

In the machine illustrated the coin-troughs b^2 b^2 are not sufficiently inclined to effect the forward movement of the stacked coin by their own weight, and the forward or downward movement is insured by the provision of gravity-acting slides E, adapted to travel in the troughs b^2 and to engage the rearmost coin of each stack, so that when the foremost coin has 80 been ejected the remaining coins of each stack will be moved forward until the lowermost coin engages the end wall a , in which position it is adapted to be engaged by the ejecting-lever when the latter is again operated. In the 85 illustrated embodiment of my invention the said slides in addition to the function just described are adapted to act as coin storing and counting devices. When used in the latter capacity, they are provided with receptacles 90 adapted to receive and carry surplus coins which are not in immediate use in making change, the said receptacles of each slide being uniform in size and adapted to receive a prescribed number of coins, so that the cashier in counting the currency need merely count the number of filled receptacles, thereby saving the time consumed in counting each coin separately. In order to increase the capacity 95 of the coin-holding slides, the receptacles are 100 formed in close proximity to each other, and to avoid difficulty of inserting and removing groups of coins therefrom some of the receptacles are relatively deep and some are relatively shallow, the same being arranged in alternate order. Thus each alternate group of coins will project above the surface of its next adjacent group, thereby presenting a gripping-surface for the fingers of the operator. In the particular construction shown the slides 105 E comprise a four-sided elongated and hollow structure having imperforate lower walls e e and slotted upper walls e' e' .

To prevent accidental or unintentional dislodgment of the slides from their places in 115 the troughs b^2 b^2 , the sides of the latter are provided with longitudinal flanges b^3 , which overhang the grooves and overlap the upper walls e' . Said flanges prevent the slide E from 120 being removed from the machine except from the rear or open ends of the troughs.

The slides E are provided each with a series of coin receptacles or slots e^2 e^3 , each slot being adapted to receive a prescribed number of coins of the same denomination as those contained in the particular groove or trough in which the slide is located. The peripheral surfaces of the coins in the slots e^2 engage the lower or bottom margins e^4 , while the side faces of the coins engage each other and the 130

side or transverse margins ϵ^5 of the slots. In the deeper slots e the peripheral surfaces of the coins rest upon the lower or bottom margin ϵ^6 of the slots and also upon the inner surface of the lower walls e ; the faces of the coins engaging each other and the side margin ϵ^7 , as clearly shown in Fig. 5.

In order that the coins as they are ejected from the troughs may be thrown forward or outwardly from the machine and will fall in such manner as to be certainly caught by or deposited in the hand of the operator, the end walls a of the troughs are inclined outwardly and forwardly or are placed at an angle to the center line of the troughs, this construction resulting in the several coins in the troughs assuming an oblique position therein, as clearly seen in Fig. 3. In connection with the inclined end walls the lower ends of the slides E are inclined to correspond with the angular position of the end walls a and so that they will be parallel with the last or rearmost coins of the stacks with which they come in contact.

One advantage of my improved construction is that only a portion of coins necessary for immediate use by the cashier need be stacked in the troughs. The remainder of the coins which are received may be lodged in the slides. Therefore when the receipt of coin o greatly exceeds the amount paid out the machine can be emptied by merely withdrawing the filled slides, the amount of money contained therein being already determined, this operation being effected without disturbing the coin stacked in the troughs. Another advantage of my improved construction is that in making change when the demand for coin of one denomination exceeds the receipts of that particular denomination the coin-stacks 40 may be quickly replenished from the slides by merely engaging the particular slide and pushing it backwardly in its trough. When the stack has been replenished, the slide being released will automatically return and engage the rearmost coin of the stack and maintain the latter in engagement with the end wall of the trough. A further advantage of my improved construction is that toward the close of a business day the cashier may transfer from the troughs to the slides coins in excess of those that are needed to finish the day's business, and at the end of the day can further transfer the remaining coins, (except coins in excess of the number required to make up complete groups to fill the receptacles,) and will then be able to easily complete the total amount of cash represented by the coin in the machine by observing the number of filled slots or compartments of the slides, the entire amount of currency contained in the machine being thus determined quickly and accurately without consuming the time of the cashier in counting the same by hand. It will be obvious that the machine herein described has the advantage of performing at once the functions

of a coin tray or holder, a coin-counter, and a change-maker.

While I have herein shown the improved gravity-acting slides as provided with coin-holding receptacles and adapted to contain currency not in immediate use in change-making, I do not wish to be limited to this particular construction of the slides, as the feature of the invention could be realized by slides adapted mainly to advance the stacked coins in the troughs.

While I have herein shown and described a specific embodiment of my invention, I do not wish to be limited to the precise form shown, as changes may be readily made without departing from the spirit of the invention.

I claim as my invention—

1. A coin-holding machine comprising a plurality of inclined coin-holding troughs adapted for the delivery of coins at their lower ends and gravity-acting slides constituting coin-receptacles and adapted to act on the coins in the troughs to advance the same into position for delivery.

2. A coin-holding machine comprising a plurality of inclined coin-holding troughs adapted for the delivery of coins at their lower ends, and gravity-acting slides adapted to travel in said troughs and advance said coins, said slides having each a plurality of coin-receptacles.

3. A coin-holding machine comprising a plurality of inclined coin-holding troughs adapted for delivery of coins at their lower ends, said troughs being of V form in cross-section and provided at the upper margins of their side walls with inwardly-projecting flanges, and gravity-acting slides constituting coin-receptacles and having inclined top and bottom walls which meet at an angle at the sides of said slides and the side margins of the inclined top walls of which are engaged with said inwardly-projecting flanges.

4. A coin-holding machine comprising a plurality of inclined coin-holding troughs adapted for the delivery of coins at their lower ends, and gravity-acting slides adapted to act on the coins to advance them in the troughs and maintain the lowermost coins in position for delivery, said slides being provided each with a plurality of coin-receptacles.

5. A coin-holding machine comprising a plurality of inclined coin-holding troughs adapted for the delivery of coins from their lower ends, and gravity-acting slides adapted to travel in said troughs, said slides comprising hollow sheet-metal structures having imperforate lower walls adapted to engage said troughs and having in their upper walls transverse slots forming a plurality of coin-receptacles.

6. A coin-holding machine comprising a plurality of inclined coin-holding troughs adapted for the delivery of coins from their lower ends, and gravity-acting slides adapted

to travel in said troughs, said slides having each a plurality of alternately deep and shallow coin-receptacles.

7. A coin-holding and change-making machine comprising a plurality of inclined coin-holding troughs adapted for the delivery of coins from their lower ends, individual ejecting mechanisms located at the delivery ends of said troughs, and gravity-acting slides constituting coin-receptacles and adapted to travel in said troughs to advance the coin therein and maintain the lowermost coins in a position to be acted upon by the ejecting mechanisms.
- 15 8. A coin-holding and change-making machine comprising a plurality of inclined coin-

holding troughs adapted for the delivery of coins at their lower ends, individual ejecting mechanisms located at the delivery ends of said troughs, and gravity-acting slides adapted to act on said coins and maintain the lowermost coin in a position to be acted upon by the ejecting mechanisms, said slides having each a plurality of coin-receptacles.

In testimony that I claim the foregoing as my invention I affix my signature, in presence of two witnesses, this 13th day of October, A. D. 1904.

JOHN W. MEAKER.
